UNITED STATES PATENT OFFICE.

CAROLINE A. PETERS, OF LOS ANGELES, CALIFORNIA.

DESIGN FOR A CHILD'S APRON.

Application filed May 23, 1925. Serial No. 13,550. Term of patent 7 years.

To all whom it may concern:

Be it known that I, CAROLINE A. PETERS, a citizen of the United States, residing at Los Angeles, in the county of Los Angeles and State of California, have invented a new, original, and ornamental Design for a Child's Apron, of which the following is a specification, reference being had to the accompanying drawing, forming a part thereof.

The figure is a front face view of a child's apron, showing my design.

I claim:

The ornamental design for a child's apron, as shown.

CAROLINE A. PETERS.
